(74) Attorney, Agent, or Firm — NIXON & VANDERHYE

(57) **CLAIM**

The ornamental design for a column as shown and described.

DESCRIPTION

1. Column

Fig. 1.1 is a top perspective view of the column, showing my new design;

Fig. 1.2 is a bottom perspective view thereof;

Fig. 1.3 is a left side view thereof;

Fig. 1.4 is a right side view thereof;

Fig. 1.5 is a front perspective view thereof; and

Fig. 1.6 is a rear perspective view thereof.

1 Claim, 6 Drawing Sheets
